UNITED STATES PATENT OFFICE.

HARRY K. WATERHOUSE, OF SAN FRANCISCO, CALIFORNIA.

IMPROVEMENT IN VEHICLE-SPRINGS.

Specification forming part of Letters Patent No. 173,834, dated February 22, 1876; application filed January 4, 1876.

To all whom it may concern:

Be it known that I, HARRY K. WATERHOUSE, of San Francisco city and county, State of California, have invented Improvements in Carriage-Springs; and I do hereby declare the following description and accompanying drawings are sufficient to enable any person skilled in the art or science to which it most nearly appertains to make and use my said invention or improvement without further invention or experiment.

My invention relates to that class of carriage springs which have devices for equalizing their action; and it consists of a combination of semi-elliptic springs with C-springs and a crank-rod connection, as hereinafter more fully described.

My improvements are fully described in the following specification, and represented in the accompanying drawings, in which—

Figure 1 is a perspective view of my carriage.

Let A represent the front and B the rear bolster of a buggy or other vehicle, and C C the reaches which connect them. D D are C-springs, which I secure in the usual way at the ends of the bolsters. The pair of C-springs at each end of the buggy or carriage I connect by a strong rod or bar, E, which has a crank, f, formed at each end. The ends of the rods outside of the cranks are secured loosely on the ends of the C-springs by coiling the springs around them, or by other equivalent means, by which the ends of the rods are journaled in the ends of the springs. A nut, g, is then screwed on the ends of the rods outside of the spring, thus giving the rod also the character of a brace to prevent the C-springs from spreading. F F are the semi-elliptic side-springs, which are secured at

their middles to the middle of the body G. The ends of these side-springs are secured loosely to the rods E E at each end of the buggy or carriage, inside of the cranks f, so that the rods can turn in the ends of the springs. It will thus be seen that the body G is suspended from the crank-rods E, and will have a longitudinal motion equal to the throw of the cranks, and that the side-springs can lengthen when depressed, without being cramped by rigid fastenings at the ends.

The combination of the side and C-springs gives an easy vertical action, while the motion of the crank-rods will relieve the stiffness or rigidity of that motion and give an easy swing to the body. The side-springs could be attached in the same manner to rigid standards or jacks so as to produce the same effect, instead of connecting them with C-springs. This arrangement also connects the action of the side-springs so as to produce an equalizing effect, as the extending of one of the side-springs by a weight placed upon one side of the buggy-body will cause the crank-rods to swing outward and thus depress the opposite spring, thus obviating the disagreeable effect of tipping the body to the side which supports the greatest weight.

Having thus described my invention or improvement, what I claim, and desire to secure by Letters Patent, is—

In a compensating vehicle-spring device the semi-elliptic side-springs F F and crank-rods E E in combination with C-springs D D, as set forth.

H. K. WATERHOUSE.
